UNITED STATES PATENT OFFICE.

JOHN A. BENTZ, OF HARRISBURG, PENNSYLVANIA, ASSIGNOR OF ONE-HALF TO
WALTER S. SCHELL AND ONE-HALF TO BESSIE M. BENTZ, BOTH OF HARRIS-
BURG, PENNSYLVANIA.

LUG.

1,369,955.

Specification of Letters Patent.

Patented Mar. 1, 1921.

Application filed January 12, 1920. Serial No. 350,852.

To all whom it may concern:

Be it known that I, JOHN A. BENTZ, a citizen of the United States, residing at Harrisburg, in the county of Dauphin and 5 State of Pennsylvania, have invented new and useful Improvements in Lugs, of which the following is a specification.

This invention relates to lugs for tractor and other wheels and its principal object is 10 to provide means whereby the lugs may be easily and quickly placed on the rim of the wheel and removed therefrom.

Another object of the invention is to make the lugs interlocking and to provide means 15 for adjustably connecting the end lugs of the series together.

A further object of the invention is to provide extensions on some of the lugs with means on the extensions for supporting an 20 extension rim.

This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:

Figure 1 is a view showing portions of a rim with my improved lugs thereon.

Fig. 2 is a similar view taken from the opposite side of the rim and at a different portion thereof.

Fig. 3 is a view of a pair of lugs.

Fig. 4 is plan view of a portion of the 40 wheel showing the extension in place.

Fig. 5 is a cross section taken on line 5—5 of Fig. 4.

Fig. 6 is a similar view of a modification.

Fig. 6^a is a sectional view of connecting 45 parts.

Fig. 7 is a detail view showing means for preventing creeping of the lugs on the rim.

Fig. 8 is a detail view of a block for lifting the wheel off the ground to permit the 50 lugs to be placed in position.

In these views 1 indicates the rim of the wheel to which my improved lugs are adapted to be secured. These lugs are shown at 2 and are formed in pairs, each pair consisting 55 of a right and a left.

The lugs extend diagonally across the outer face of the rim and the ends of each lug are offset as at 3. These offset ends are formed to provide the channels or grooves 4 to receive the extensions of the rim and the 60 groove at one end of each lug is of greater width than the groove at the other end of the lug so that a space will be formed between the inner face of the rim and the inner wall of this groove. This space is to receive a tongue 5 which is carried by the abutting part of the adjacent lug, and has its end bent at right angles as at 6 to lock the two parts together. As will be seen each lug has one end provided with the wide 65 groove and its other end carries the tongue. In this way each lug interlocks at each end with the adjacent lug.

As will be seen the abutting lugs extend in opposite directions diagonally of the rim 75 and form a zigzag rim or projection around the rim.

The abutting ends of the end lugs of the series are adjustably connected together by the bolt 7 which passes through the perforated ears 8 projecting from the inner faces of the offset parts of the lugs and by rotating the nut 9 on said bolt the series of lugs may be tightened on the rim. 80

In order to prevent creeping of the lugs 85 on the rim I provide a plate 10, which is shown in detail in Fig. 7, said plate having the screw threaded projections 11 for engaging the holes 12 in the rim and held therein by suitable nuts or the like. This plate is 90 provided with a hole 13 for receiving the bolt 7, said plate having a portion located between the offset portions which carry the ears 8. By this means the end lugs of the series are kept from sliding on the rim and 95 prevent the whole series of lugs from creeping.

In order to raise the wheel off the ground to permit the lugs to be placed entirely around the rim I provide a block 14, which 100 is shown in detail in Fig. 8, and this block is provided with a curved slot 15 to receive the edge of the rim. This block is placed on the rim and the vehicle is then moved to bring the block in contact with the ground, whereby the block will raise the wheel from the ground and permit the lugs to be placed on the lower part of the rim.

I provide some of the lugs with extensions 16 which extend at right angles from

the rim and are adapted to support an extension rim 17. These extensions 16 are of the same thickness as the body of the lugs so that the offset parts and the bent end 16' 5 of the extensions form a channel in each extension to receive the extension rim. If necessary or desired, as shown in Fig. 6, I may provide the parts 16' with an inwardly extending part 16'' forming a groove 16'' 10 to receive the outer edge of the extension rim. When the groove 16'' is provided the extensions are made of such a length as to permit the extension rim to pass between the end of the part 16'' and the outer wall 15 of the offset part. The extension rim is then forced outwardly to cause its edge to engage the grooves 16'' and the rim is held in this position by blocks 18 placed between the two rims and held in place by bolts or 20 the like.

It will thus be seen that the connecting means of the lugs are located on the inner parts of the members so that said means will not come in contact with the ground, 25 also that the lugs interlock with one another whereby when all the lugs are assembled and the end lugs connected together by the bolt the series of lugs will be locked to the rim and held against movement thereon.

30 It is thought from the foregoing description that the advantages and novel features of my invention will be readily apparent.

I desire it to be understood that I may make changes in the construction and in 35 the combination and arrangement of the several parts, provided that such changes fall within the scope of the appended claims.

What I claim is:

1. Traction lugs for vehicle wheels comprising a plurality of diagonally arranged members, alternate members extending in opposite directions the ends of the members having portions overlapping the edges of the rim, and interlocking means formed on 40 said overlapping portions and arranged on the inner side of the rim for connecting the lugs together.

2. Traction lugs for vehicle wheels comprising a plurality of diagonally arranged members, said members being arranged in pairs, the members of each pair extending in opposite directions, offset portions at the 50 ends of each member, each portion having a groove therein for receiving the edge of the rim, the groove at one end of each member being of greater width than the groove at the other end and a tongue on said other end for engaging the wide groove in the adjacent member.

60 3. Traction lugs for vehicle wheels comprising a plurality of diagonally arranged members, said members being arranged in pairs, the members of each pair extending in opposite directions, offset portions at the 65 ends of each member, each portion having

a groove therein for receiving the edge of the rim, the groove at one end of each member being of greater width than the groove at the other end and a tongue on said other end for engaging the wide groove in the adjacent member, said tongue having a projection thereon for locking the tongue in said pair. 70

4. Traction lugs for vehicle wheels comprising a plurality of diagonally arranged members, alternate members extending in opposite directions, each member having its ends overlapping the edges of the rim, and interlocking means formed on the inner parts of the overlapping portions of adjacent members for locking said members together, one of such means being adjustable. 75

5. Traction lugs for vehicle wheels comprising a plurality of diagonally arranged members arranged in pairs with the members of each pair extending in opposite directions, each member having its ends overlapping the edges of the rim, means on the inner faces of the overlapping portions of adjacent members for locking said members together, one of such means being adjustable, 85 said adjustable means consisting of a pair of ears projecting from the inner faces of the adjacent overlapping parts and a bolt passing through said ears and a nut on said bolt. 90

6. Traction lugs for vehicle wheels comprising a plurality of diagonally arranged members arranged in pairs with the members of each pair extending in opposite directions, each member having its ends overlapping the edges of the rim, means on the inner parts of said overlapping portions for locking the adjacent portions together, one of such means being adjustable and means 100 associated with the adjustable means for preventing creeping of the lugs on the rim. 105

7. Traction lugs for vehicle wheels comprising a plurality of diagonally arranged members arranged in pairs with the members of each pair extending in opposite directions, each member having its ends overlapping the edges of the rim, means on the inner parts of said overlapping portions for locking the adjacent portions together, one 110 of such means being adjustable, means associated with the adjustable means for preventing creeping of the lugs on the rim, said anti-creeping means consisting of a plate detachably connected with the rim and adapted to 115 fit between the inner parts of the overlapping portions and having a hole therein for receiving the bolt. 120

8. Traction lugs for vehicle wheels comprising a plurality of diagonally arranged members arranged in pairs with the members of each pair extending in opposite directions, said members having end portions overlapping the edges of the rim, means on the inner parts of said overlapping portions 125 130

for locking the members together, extensions on some of said members and means on said extensions for supporting an extension rim.

9. Traction lugs for vehicle wheels comprising a plurality of diagonally arranged members arranged in pairs with the members of each pair extending in opposite directions, said members having end portions overlapping the edges of the rim, means on the inner parts of said overlapping portions for locking the members together, extensions on some of said members, means on said extensions for supporting an extension rim, such means consisting of a channel formed in each extension and a groove in the outer end of each extension and blocks adapted to be placed between the two rims for holding the edge of the extension rim in said groove.

10. The combination with a wheel rim, of a series of traction lugs secured thereto and lateral extensions provided on the lugs forming a support to which a supplemental rim may be attached.

11. The combination with a wheel rim, of a series of traction lugs extending around the periphery of the same, each provided with means interlocking with the edge of the rim, each of said lugs having its end detachably interlocking with the ends of adjacent lugs, recessed portions carried by certain of the lugs, and an auxiliary rim engaging the recessed portions of said lugs.

12. The combination as defined in claim 11, provided with means for locking the auxiliary rim in the recessed portions of said lugs.

13. The combination with a wheel rim, of a series of traction lugs extending around the periphery of the same, each of said lugs having its ends detachably connected to the wheel rim and to the ends of adjacent lugs, certain of said lugs being provided with re-

cessed portions which extend parallel to the axis of the rim, an auxiliary rim co-axial with the wheel rim and having a portion 45 located in said recesses, and means for locking said auxiliary rim in said recesses.

14. The combination with a wheel rim, of a series of traction lugs extending around the periphery of the same, each of said lugs 50 extending diagonally across the periphery of the rim and having its ends interlocking with the edges of the rim, the ends of each lug being interlocked with the ends of adjacent lugs, certain of said lugs being provided with recessed portions, an auxiliary rim mounted in the recessed portions of said lugs, means for locking the lugs upon the wheel rim and means for locking the auxiliary rim in said recesses.

15. The combination as defined in claim 14, in which the first named means consists of a single bolt and nut.

16. The combination with a wheel rim, of a series of traction lugs extending around the periphery of the same, certain of the lugs being provided with projecting portions extending parallel to the axis of the rim and beyond one edge of said rim, recesses provided in the extending portions of said lugs, 70 and an auxiliary rim resting in said recesses.

17. The combination as defined in claim 16 having locking means for the auxiliary rim located between said rims.

18. Traction lugs for vehicle wheels, comprising a plurality of diagonally arranged members, alternate members extending in opposite directions, the ends of the members having portions overlapping the edges of the rim, and interlocking means formed on 80 said overlapping portions for connecting the lugs together.

In testimony whereof I affix my signature.
JOHN A. BENTZ.
